UNITED STATES PATENT OFFICE.

PRESTON L. SMITH, OF PHILADELPHIA, PENNSYLVANIA, ASSIGNOR OF ONE-THIRD TO ALFRED DAY AND ONE-THIRD TO JOHN C. BREITHAUPT, OF PHILADELPHIA, PENNSYLVANIA.

AUTOMATIC ENDING-MACHINE FOR BOXES.

No. 852,083.

Specification of Letters Patent.

Patented April 30, 1907.

Application filed January 5, 1906. Serial No. 294,722.

To all whom it may concern:

Be it known that I, PRESTON L. SMITH, a citizen of the United States, residing in the city and county of Philadelphia, State of Pennsylvania, have invented a new and useful Improvement in Automatic Ending-Machines for Boxes, of which the following is a specification.

My invention relates to paper box machines and consists in a novel construction of a machine, whereby I am enabled to simultaneously secure the two ends to the box.

It further consists of automatic means for applying the adhesive material to the box ends at the desired point in a very even and reliable manner.

It further consists of a novel construction of an adjustable receptacle for the box ends and of novel means for simultaneously bringing a box end into operative position with respect to the box to which it is to be secured.

It further consists of a novel construction of feeding mechanism for the box ends by means of which a single box end is removed from its receptacle and rotated sufficiently to bring it into alignment with the box end of the box support.

It further consists of a novel construction of lifting mechanism for automatically raising the box above its support after the ends have been secured thereto.

It further consists of a novel construction of a carrier by means of which the finished boxes are automatically removed from the lifter and carried to the desired point.

It further consists of a novel construction of clamping mechanism whereby the box is automatically clamped in position.

It further consists of a novel construction of receptacles for the paste or other adhesive material having valved openings therefor, which are adapted to be actuated by the engagement of the valve stems with the box ends.

It further consists of a novel construction of a pressing device mounted on reciprocating cross-heads and adapted to receive and retain a single box end which is fed thereto by the feeding mechanism.

It further consists of a novel manner of supporting a box end on the pressing mechanism and novel means for adjusting the size of this support.

It further consists of a novel means for adjusting the pressing devices with respect to the adjustable box support.

It further consists of other novel features of construction, all as will be hereinafter fully set forth.

Figure 1 represents a front elevation of the machine. Fig. 2 represents a side elevation of certain detached portions of the machine. Fig. 3 represents an end elevation of the machine with certain of its parts removed therefrom. Fig. 4 represents a plan view of a portion of the machine. Fig. 5 represents a side elevation on an enlarged scale, of certain detached portions of the machine. Fig. 6 represents an end elevation, partly in section, of a portion of the machine. Fig. 7 represents a side elevation of certain detached portions of the machine. Fig. 8 represents an end elevation, partly in section, of certain of the parts seen in Fig. 7. The section is taken on line $x-x$, Fig. 7. Fig. 9 represents an end elevation of certain of the parts seen in Fig. 8. Fig. 10 represents an end view of a portion of the machine. Fig. 11 represents a view of certain of the parts seen in Fig. 10 and viewed from a point at a right angle thereto. Fig. 12 represents a perspective view of certain detached parts of the machine. Fig. 13 represents an elevation of a portion of the gumming device with valves therein, and on an enlarged scale. Fig. 14 represents a horizontal section on line $y-y$, Fig. 13, with certain of the parts removed. Fig. 15 represents a perspective view of the body portion of a box. Fig. 16 represents a perspective view of one of the end pieces of a box. Fig. 17 represents a perspective view of a finished box. Fig. 18 represents a side elevation of a modification.

Similar numerals of reference indicate corresponding parts in the figures.

Referring to the drawings:—1 designates the frame of the machine in which is journaled the main shaft 2 which has loosely mounted thereon, a pulley 3 provided with a clutch member 4 which co-acts with the member 5 that is splined on the shaft 2, said member 5 being brought in and out of engagement with the member 4 by a lever 6^a in the usual manner. The shaft 2 has a pinion 6 fast thereon which meshes with a gear

wheel 7 fast on the shaft 8. The shaft 8 has secured thereon the eccentrics 9 and 10, the sprocket wheels 11 and 12 and a cam 13. The sprocket wheel 11 imparts motion to a sprocket chain 14 which passes partly around a sprocket wheel 15, which is fast on a shaft 16, journaled in the frame 1. The shaft 16 has secured thereon a bevel gear wheel 17 which meshes with a gear wheel 18 secured 5 to a shaft 19 that is journaled in the frame 1, and has secured thereon a crank disk 20 on whose wrist pin 21 is coupled one end of a link 22 whose opposite end is coupled at 23 to an arm 24, secured to a shaft 25 which is 10 journaled in the standards 26 and 27, and is adapted to rock said shaft, for a purpose hereinafter described.

It will be understood that power is imparted to the pulley 3 in any manner as by a 15 belt 28.

The eccentrics 9 and 10 are each provided with a connecting rod 29, the outer end of which is pivoted at 30 to its respective lever 31, which are fulcrumed at 32 in the frame 1 20 and the upper end of each of said levers is connected, as at 33 and in any suitable manner, with a projecting member 33^a of its respective cross-head 34, which is guided in the frame 1. Guided in the frame 1 are the 25 plates 35, in each of which is swiveled a right and a left hand threaded screw 36 which engages the plates 37 and 38, respectively, so as to cause said plates to either approach or recede from each other, for a purpose herein- 30 after described. The plates 37 and 38 have, each pivoted thereto, at 39, a bar 40 which serves as a clamp to retain the sides 41 of the body portion 42 of a paper box, seen in Fig. 15, against the plates 37 and 38 upon which 35 said body portion 42 is placed. The bars 40 are retained, normally, in their opened positions by springs 43, as seen in Figs. 6, 7 and 8. The bars 40 are each provided with a roller 45 which is in the path of the cams 46, 40 it being noted that the bars 40 are, in the present instance, four in number, as illustrated in Fig. 4, and the cams 46 are two in number and that each of said cams acts in conjunction with the two rollers 45 that are 45 adjacent thereto, as hereinafter described.

Rising from the cross-heads 34 are plates 47 in which are loosely fitted the rods 48 whose inner ends are firmly secured to the plates 49, which are integral with or may 50 have secured thereto, the cams 46. The rods 48 are secured in any suitable manner, as for instance by the bolts 53, see Fig. 7, to their respective plates 50 so that said plates, 55 their rods 48, the plates 49 and the parts carried by the latter all move as one, for a purpose hereinafter described.

The rods 48 are each encircled by a spring 51, one end of which bears against a threaded sleeve 47' which has threaded engagement 60 with a plate 47, while its opposite end bears

against its adjacent plate 50. The free ends of the rods 48 are provided with nuts 52 which serve as abutments for the plates 47 in connection with the springs 51.

The plates 49 are provided with catches 54 70 against each of which bears a spring 55 which normally retains said catches in their forward position so as to cause their points to project beyond their respective plates 49. The plates 49 are each provided with a ledge 75 56 which rests upon springs 57 and have a slot therein through which passes a rod 59 which has pivoted thereto a cam 60 that bears against a plate 61 so as to clamp said ledge 56 in its adjusted position; it being 80 noted that the ledge 56 is fitted in a slot 62, in the plate 49, to permit its adjustment relatively to the catches 54, for a purpose herein- 85 after described. The end of the rod 59, opposite that in which the cam 60 is pivoted, is secured to a plate 63. The springs 57 are each supported, preferably, in a socket in a block 64 provided with bolts 65 which are fitted in slots 66, see Fig. 9, in the plates 49 to permit said block 64 to be raised and 90 lowered to conform to the adjustment of the ledge 56.

The plates 35 are each provided with a projecting member 67 which partly fills the gap between the plates 37 and 38, see Figs. 95 6, 7, and 8, so as to provide an abutment at this point for the inturned edges 68 in the ends of the body portion 42 of a box. The cross-heads 34 are each provided with a toothed rack 69, see Fig. 1, with which engages the screw threaded portions 70 of a rod 71, which when a revolving motion is imparted thereto causes said cross-heads 34 to either approach or else recede from each other. The frame 1 of the machine is provided with toothed racks 72 with which engage the worms 73, which latter are splined on the rod 71 so as to be rotated thereby and by reason of their engagement with the racks 72 will cause the plates 35 to follow the movement imparted to the cross-heads 34 by the rotation of said rod 71 so that no relative movement occurs between a plate 35 and the plate 49 adjacent thereto.

The frame 1 has secured thereto the 115 blocks 74 which serve as stops to limit the outward movement of the plates 49. Guided in ways 75, in the frame 1, is the cross-head 76 which is provided with a roller 77 which is in contact with the cam 120 13, as best seen in Fig. 12, it being noted that said cross-head 76 has connected therewith the bar 78 which is provided with slots 79 through which are passed the bolts 80, which are also passed through the bars 81 125 so as to secure the same to the bar 78, for a purpose hereinafter described. The bars 81 have fitted thereon the bars 82 which have slots 83 therein, through which are passed the bolts 84 which retain said bars 130

82 in their adjusted positions relatively to the size of the paper boxes to which their end portions 85 are to be affixed.

The standards 26 and 27 are each provided with guide pulleys 86, partly around which are passed their respective cords 87 to one end of each of which is secured a weight 88. The opposite end of each of said cords 87 is secured to its respective follower 89, which 10 bears against a stack of end portions 85, placed in said standards 26 and 27 and feeds said end portions 85 to the grippers or feed plate 90, which are carried by the arms 91 fast on the shaft 25, for a purpose hereinafter 15 described. Loosely fitted on the shaft 25 are arms 92 which co-act with their respective arms 91, as hereinafter described. The grippers 90 each consist of a head 93 which is free to turn on its axis or journal 94, 20 see more particularly Fig. 5. The heads 93 are each provided with a spring 95, a stop 96 and a serrated plate 97, the object of all of which is hereinafter described. The arms 91 have pivoted thereon their respective 25 arms 98 in which are the journals 94 of the heads 93. The arms 91 are each provided with a stop 99 which limits the movement of its arm 98 in one direction against the action of its spring 100. The arms 91 have each 30 loosely fitted therein a rod 102 which is encircled by a spring 101, one end of which bears against its respective arm 91, while its opposite end bears against a nut 101^a fitted on said rod. The rod 102 has a head 35 144 thereon, for a purpose hereinafter described.

The standards 26 and 27 are provided with the members 103 and 104, which have fitted therein, the blocks 105, which act as 40 guides for the end portions 85, hereinbefore referred to, and which may be adjusted relatively to different sizes of boxes. The guides 105 are retained in their adjusted positions by tap bolts 106 which are screwed 45 into the guides 105, it being noted that said bolts 106 pass through slots 107, in the members 103 and 104, whereby said guides 105 may be moved along the members 103 and 104.

50 The arms 92 are each provided with a spring 108 which retains said arms in their proper positions relatively to their respective arms 91.

The standards 26 and 27 have each a rod 109 55 swiveled therein as at 110, in Figs. 3, 10 and 11, it being noted that said rods 109 are each provided with a left and a right hand screw thread which engage the members 103 and 104 respectively, so that the two latter may 60 be adjusted relatively to each other according to boxes of different sizes. The rods 109 have the hand wheels 111 secured thereon whereby said rods may be readily operated. The standards 26 and 27 have each pivoted 65 thereon at 112, the reservoirs 113 with which

are connected the pipes 114, it being noted that said pipes consist of sections pivoted together whereby they may turn on their pivotal connections, for a purpose hereinafter described. Certain of the pipes 114 discharge an adhesive material, contained in the reservoirs 113, into the hollow frames or receptacles 115 from which a portion of said material flows into the receptacles 116, for a purpose hereinafter described. The receptacles 116 are each connected by set screws 117 to their respective pipe 118, which depends from the reservoirs 113, as seen in Figs. 1 and 3, and supply adhesive material to the receptacles 116. The pipes 118 are 80 opened and closed by their respective valve 145, and the pipes 114 are opened and closed by their respective valve 146.

The receptacles 115 and 116 are provided with openings 119, see Fig. 14, in each of 85 which is fitted a valve 120 whose plug 121 is normally seated on the parts 122 so as to close the same, it being noted that said plug is provided with a stem 133 a portion of which projects beyond the face of said valve, 90 for a purpose hereinafter described, and, furthermore, that said stem 123 is encircled by a spring 124 whose object is to retain the valve 120 normally closed. The members 125 of the frames 116, are each in contact with 95 their respective cam 126 which is secured on the shaft 25, as seen in Fig. 1. The standards 26 and 27 are in engagement with a rod 127, swiveled in the frame 1, it being noted that said rod 127 has a right and a left hand 100 screw thread thereon so that when it is rotated it causes the standards 26 and 27 to either approach or else recede from each other, according to the direction in which said rod 127 is turned.

The sprocket wheel 12, as seen in Fig. 6, 105 imparts motion to the sprocket chain 128, which is in engagement with a sprocket wheel 129 that is splined on the shaft 130 which is journaled in a standard 131 secured to the frame 1. Guided in ways 132, in the frame 1, is a plate 133 in which is a slot 134 through which passes a clamp screw 135 whose object is to retain said plate 133 in its adjusted position. Rising from the plate 133 is a frame 110 136 in which is journaled a shaft 137 which has secured thereon, the bevel gear wheel 138 which meshes with a bevel gear wheel 139 fast on the shaft 130. The shaft 137 has secured thereon, the sprocket wheels 140, in 115 the present instance two in number and partly around which latter are passed the sprocket chains 141 which also pass partly around the sprocket wheels 142, see also Fig. 1, journaled in the frame 136. The sprocket 120 chains 141 are provided with hooks 143 that are adapted to take hold of a paper box, when finished, and remove it from the machine.

The operation is as follows:—The rod 71 130

is rotated, either from right to left or vice versa, so as to cause the cross-heads 34 to be brought either closer to or away from each other according to the length of the boxes to which the end portions 85 are to be affixed. It is apparent that the parts carried by said cross-heads will follow the movements of the latter. The rotation of the rod 71 imparts motion to the plates 35, by reason of the worm 73, and causes them to move in unison with the cross-heads 34 and locate them in a proper position relatively to the parts on the cross-heads 34. The rods 36 carried by the plates 35 are then rotated whereupon the plates 37 and 38 are caused to either move toward or away from each other according to the direction in which said rods are rotated and thus adjust said plates relatively to the width of the boxes to which the end portions 85 are to be affixed. The rods 109 which are employed for regulating the size of the box end receptacle are then rotated and cause the members 103 and 104 to be brought either toward or else away from each other according to the length of the end portions 85 of a box, after which the guides 105 are moved either inwardly or outwardly according to the width of the end portions 85 of a box and are retained in their adjusted positions by the clamping screws 106. The receptacles 115, for the adhesive material, are then brought either nearer to, or away from each other by the operator so as to be properly located relatively to the members 103 and 104, it being apparent that the pivoted sections of pipe 114 permit of this adjustment, and that when the parts are in proper position, certain of the pivotal joints in the pipes 114 are tightened so as to retain the said pipes and the receptacles 115, firmly, in their adjusted position. A follower 89 is then brought into its extreme outward position and a plurality of end portions 85, for the boxes, are placed in their respective standard 26 or 27, it being understood that both standards are supplied with end portions 85. As soon as the follower 89 is released, the weight 88 connected therewith exerts a pull thereon and causes the follower to bear against the end portions 85 to feed them to their respective grippers 90.

Assuming that the reservoirs 113 are supplied with an adhesive material it is evident that when the valves 145 and 146 are opened this material will flow through their respective pipes and fill the receptacles 115 and 116 with the same. A body portion 42 of a box is then placed, in an inverted position, on the forms or plates 37 and 38, after which the clutch member 5 is shifted so as to cause it to interlock with the clutch member 4 whereupon the machine is put in motion. This causes the shaft 8 to rotate and impart motion to the eccentrics 9 and 10 whereupon the crossheads 34 are caused to reciprocate

by the connecting mechanism between the parts. The rotation of the shaft 8, by reason of the sprocket wheels 11 and 15, the chain 14 and the bevel gear wheels 17 and 18 impart a rotary motion to the crank disk 20 which by reason of the link 22 and arm 24, transmits a partial rotation or rocking motion to the shaft 25 and consequently to the arms 91 and the cams 126. When the cross-heads 34 move inwardly by the action of the eccentrics 9 and 10 they carry the plates 47 which bear against the springs 51 and these latter transmit motion to the plates 50 which by reason of their connection with the rods 48, impart a motion to the plates 49. When the shaft 25 is rocked and brought into a position corresponding to approximately the quarter of a revolution from the position seen in Fig. 1, the cams 126 permit the receptacles 115 and 116 to move toward the standards 26 and 27 and when the stems 123, in the valves 120 are brought in contact with an end portion 85 they are moved inwardly and open said valves and permit some of the adhesive material in said receptacles to escape therefrom and adhere to those parts, of the end portions 85, that are brought in contact with the inturned edges 68. The cams 126 are so shaped that the time in which the valves 120 remain open is of comparatively short duration. In the meantime the arms 91 have also made a quarter of a revolution whereupon the end portion 85 which was in contact with its respective gripper 90, when the arms 91 were in a vertical position, is now brought into a position in alignment with the inturned edges 68 of the body portion 42 of the box supported upon the plates 37 and 38. When the arm 91 is turning in the direction indicated by the arrow in Fig. 11 it carries with it an end portion 85, during which time the arm 92 remains stationary and does not turn until the head 144 is brought in contact therewith and this occurs when the arms 91 and 92 are parallel with each other, it being apparent that the end portion 85 is now carried by both of said arms, between which it is located and firmly held in position after leaving the standard 27. On the return movement of the shaft 25 the cams 126 return to the position seen in Fig. 1, whereupon the receptacles 115 and 116 are swung outwardly from the end portions 85 and close the valves 120 and furthermore leave room for the arms 91 which are returning to their vertical positions. When the grippers 90 have brought their respective end portions 85, of a box in the desired position relatively to the body portion 42 thereof, said grippers are carried back to their former positions with the arms 91, to which they are secured, it being understood that the serrated plates 97 release the end portions 85 by reason of the yielding of the springs 95 which permit said

plates 97 to slide on the end portions 85 on their return movement prior to bringing forward a subsequent end portion 85. The springs 100 yield and thus permit the plates 5 97 to ride over obstructions in the end portions 85 if such obstructions exist. When a gripper 90 has completed its downward stroke it places an end portion 85 between a catch 54 and a ledge 56, see Fig. 7, whereupon 10 said end portion 85 is securely retained in position in a plate 49 prior to its being carried forward, as hereinbefore described. When the plates 49 complete their forward movements, they press the end portions 85, carried thereby, firmly against the inturned edges 68 and cause them to adhere thereto. The cams 46 engage the rollers 45 and cause the bars 40 to clamp the body portion 42 of a box firmly in position on the plates 37 and 20 38, while the end portions 85 are being gummed thereto. When the clamping bars 40 release their hold on the body portion 42 of a box, the cam 13 seen in Figs. 12 raises the bars 82 and consequently the body portion 42 of a box with its end portions 85 secured thereto and brings it in position to be taken up and removed from the machine by the hooks 143 on the sprocket chains 141, see Fig. 6. The finished boxes slip off the 30 hooks 143 when the latter reach the point indicated at "B" in Fig. 6 and from which point they may be directed to any desired spot.

It will be apparent that in the broad scope 35 of my invention after the box support and the receptacles for the box ends have been adjusted to the proper size it is only necessary to place a box, which has been weakened or bent in the usual manner, on the box support and then start the machine. The entire operation of clamping the box to its support, applying the paste to the box ends, feeding the box ends into their proper position with respect to the supported box, simultaneously 40 securing the two ends to the box, raising the box above its support and removing the finished box to a desired place, is entirely automatic. The different parts of the machine may be readily and quickly adjusted 45 according to the size of the box and box ends which it is desired to secure together. It will be apparent that while I have described the device as adapted to secure the ends to a box, other portions of a box such as the sides 50 or other parts may be secured thereto, if desired and still be within the scope of my invention.

In order to adjust the tension of the springs 55 1 I employ threaded sleeves or bushings 60 47' which are fitted in threaded openings in the plate 47 and have the bolts 48 pass through the same, the springs being seated against the ends of the sleeves so that by operating the latter in either direction more

or less pressure may be imparted to said 65 springs, the effect of which is evident.

Having thus described my invention, what I claim as new and desire to secure by Letters Patent, is:—

1. In a box ending machine, a support for 70 the box, clamping bars pivoted to said support, means for maintaining said clamping bars normally open, rollers carried by said bars, crossheads movable with respect to said support, means for feeding the box ends 75 thereto, means for applying adhesive material to said ends, and means yieldingly actuated for simultaneously securing said ends to said box.

2. In a box ending machine, a box support, 80 means for adjusting the size thereof, clamping bars pivoted to said support, means for maintaining said clamping bars normally open, rollers carried by said bars, crossheads movable with respect to said support, a feed- 85 ing device for the box ends, means for automatically clamping a box on said support, and means yieldingly actuated for simultaneously securing the ends to said box.

3. In a box ending machine, an adjustable 90 box support, clamping bars pivoted thereto, means for actuating said bars, an adjustable support for the box ends, means for applying adhesive material to said ends, means for simultaneously bringing the ends into alignment with said box, and means yieldingly actuated for pressing said ends against said box. 95

4. In a box ending machine, an adjustable 100 box support, clamping bars pivoted thereto, means for actuating said bars, an adjustable support for the box ends, means for applying adhesive material to said ends, means for simultaneously bringing the ends into alignment with said box, means yieldingly actuated for pressing said ends against said box, and means for automatically removing 105 the finished boxes from said box support.

5. In a box ending machine, a support for 110 the box, clamping bars pivoted to said support, means for actuating said bars, means for feeding the box ends thereto, means for applying adhesive material to said ends, means yieldingly actuated for simultaneously securing said ends to said box, and means for 115 adjusting said last mentioned means with respect to said box support.

6. In a box ending machine, a box support, means including bars pivoted to said support for automatically clamping a box thereon, adjustable means for bringing the box ends into operative position, means for applying adhesive material near three edges of each end, and tension means for simultaneously securing the ends in position. 120

7. In a box ending machine, a box support, a frame adjustably secured with respect to said support, a plurality of sprocket wheels 125

- mounted thereon, an endless chain engaging said sprocket wheels, hooks carried by said chain adapted to remove a box from said support, and means for rotating one of said 5 sprocket wheels.
8. In a box ending machine, a frame having a guideway thereon, a box support adjustably mounted in said guideway, cross-heads adjustably mounted in said guideway, 10 plates mounted on said crossheads, plates yieldingly connected therewith and adapted to support a box end, and means for reciprocating said crossheads.
9. In a box ending machine, a box support, crossheads movable toward and away from said support, a plurality of plates mounted on each crosshead, a plate yieldingly connected with each plurality of plates, a ledge adjustably mounted on said plate 15 adapted to support a box end, and means for actuating said crossheads.
10. In a box ending machine, a box support, crossheads movable toward and away from said support, a plurality of plates mounted on each crosshead, a plate yieldingly connected with each plurality of plates, a ledge adjustably mounted on said plate 20 adapted to support a box end, a catch for the box end yieldingly carried at the upper end of said plate, and means for actuating said crossheads.
11. In a box ending machine, an adjustable box support, clamping bars pivoted thereto, rollers carried by said bars, cross-heads movable with respect to said support, a plurality of plates mounted on each cross-head, a plate yieldingly connected with each plurality of plates and adapted to support a box end, a cam carried by said plate for 25 actuating said clamping bars, and means for reciprocating said crossheads.
12. In a box ending machine, an adjustable box support, clamping bars pivoted thereto, means for maintaining said clamping bars normally open, rollers carried by said bars, crossheads movable with respect to said support, a plurality of plates mounted on each crosshead, a plate yieldingly connected with each plurality of plates and adapted to support a box end, a cam carried by said plate for 30 actuating said clamping bars, and means for reciprocating said crossheads.
13. In a box ending machine, an adjustable box support, an adjustable support for the box ends, means for applying adhesive material to said ends, means for simultaneously bringing the ends into alinement with said box, means for pressing said ends against said box, means for automatically raising the 35 finished box above its support, and means for removing the finished box.
14. In a box ending machine, a driven shaft, a cam thereon, a crosshead, a roller mounted thereon and coating with said 40
- cam, a box lifter comprising a plurality of laterally adjustable members connected with said cross head, and means for adjusting the size of said lifter.
15. In a box machine, a driving shaft, a driven shaft, eccentrics mounted on said driven shaft, crossheads operatively connected with said eccentrics and reciprocated thereby, an adjustable box support adjustably mounted on said crossheads, means actuated by the driving shaft for applying adhesive material to the box ends, means for feeding the box end into position, and yielding means mounted on each of said cross heads for simultaneously pressing the two ends against a box on said box support. 45
16. In a box ending machine, a box support having end sections comprising a fixed central section and movable side sections, a screw having a right and a left thread thereon engaging said sections, said right thread 50 engaging said central and one side section, said left thread engaging said central and the other side section, clamping devices carried by said support, tension devices therefor, and means for longitudinally adjusting the size of said support.
17. In a box ending machine, a driven shaft, a cam thereon, a crosshead mounted on said shaft, a roller carried by said crosshead, a slotted arm connected with said crosshead, bars adjustably secured in said slots, and supports for a box carried by said bars and longitudinally adjustable thereon. 55
18. In a box ending machine, a frame, crossheads thereon, means for reciprocating said cross-heads, an adjustable box support located between said cross-heads, clamping means carried by said support, and means carried by said cross-head for actuating said clamping means. 60
19. In a box ending machine, a frame, an adjustable box support thereon, cross-heads between which said support is mounted, means for reciprocating said cross-heads, a fixed plate carried by each cross-head, rods 65 connected with said plates, recessed plates secured to said rods, ledges adjustably mounted in said recesses and each adapted to support a box end, and catches at the upper end of said plates adapted to engage said box ends. 70
20. In a box ending machine, cross-heads adapted to be reciprocated, a plate mounted on each cross-head, rods extending through said plate, a second plate carried by said cross-heads, springs interposed between said plates, and a plate secured to said rod adapted to support a box end. 75
21. In a box ending machine, cross-heads adapted to be reciprocated, a plate mounted on each cross-head, rods extending through said plate, a second plate adjustably mounted on said rods, springs interposed between 80

said plates, a plate adapted to support a box end secured to said rods, and a plate secured to said rods adapted to support a box end.

22. In a box ending machine, cross-heads 5 adapted to be reciprocated, a plate secured to each cross-head, rods passing through said plates, a second plate adjustably mounted on said rods, springs interposed between said plates, a plate adapted to support a box end secured at the ends of said rods and means for locking a box end in position thereon.

23. In a box ending machine, an adjustable box support, clamping bars pivoted thereto, rollers carried by said bars, cross-heads adapted to be reciprocated, supports 15 for a box end yieldingly mounted on each cross-head, means for locking the box end in position on its support, and means carried by said box end support adapted to co-act 20 with said rollers to actuate said clamping bars.

24. In a box ending machine, an adjustable box support, clamping bars pivoted thereto, rollers carried by said bars, cross-heads adapted to be reciprocated, support 25 for a box end yieldingly mounted on each cross-head, means for locking the box end in position on its support, and cams carried by said box end support adapted to co-act with 30 said rollers to actuate said clamping bars.

25. In a box ending machine, an adjustable box support, a box end receptacle in proximity thereto, a shaft suitably mounted with respect to said receptacle, a lever fixed on said shaft, arms extending from said shaft, a 35 roller mounted in said arms, a spring carried by said lever engaging said roller, a stop for said arms carried by said lever, a feed plate secured to said roller, means for partially rotating the said shaft, and means coacting 40 with a box end and including a lever loosely mounted on said shaft between which and said feed plate a box end is supported and brought into proper position with respect to 45 said box support.

26. In a box ending machine, an adjustable box end receptacle, a receptacle for adhesive material supported in proximity to said box end receptacle, a pipe having swiveled connections connected therewith, paste 50 receptacles connected with said pipe, a second pipe extending from said receptacle for the adhesive material, a third paste receptacle in communication with said second pipe, a valve for said pipe, and a valve for said first mentioned pipe. 55
